UNITED STATES PATENT OFFICE.

CHARLES ALFRED JAMES, OF LONDON, ENGLAND.

VESSEL NAVIGABLE IN WATER, AIR, OR BOTH.

1,331,925.

Specification of Letters Patent. Patented Feb. 24, 1920.

Application filed September 10, 1919. Serial No. 322,973.

To all whom it may concern:

Be it known that I, CHARLES ALFRED JAMES, a subject of the King of Great Britain, residing at 148 Upper Clapton road, 5 (E. 5,) London, England, have invented new and useful Improvements in Vessels Navigable in Water, Air, or Both, of which the following is a specification.

My invention relates to an improved boat 10 or vessel which is navigable in the water or partly in the water and partly in the air and which under certain circumstances may be caused to rise off the water and float wholly in the air, the object of my invention being 15 to provide a vessel capable of attaining a greater speed than can be obtained with vessels as heretofore constructed.

The hull of my improved boat somewhat resembles that of a flat bottomed boat heretofore proposed having a continuously and 20 practically uniformly increasing draft from the water level toward the bow to a maximum at the stern.

According to my invention, however, the 25 flat bottom of the boat is extended upward above the water line for a large proportion of the length of the vessel, the bow or stem of the vessel is considerably above the water level, whereby as the boat is propelled re- 30 action takes place between the immersed portion of the bottom and the water and between the unimmersed portion of the bottom and the air, the united reactions tending to lift the boat and thereby reduce the immersion 35 and consequent water friction. Furthermore the sides of the hull gradually diverge from the stern toward the bow which is the widest part of the vessel.

As the speed of the boat increases the re- 40 action of the air and water against the inclined bottom will tend to increase the inclination of the latter to the horizontal and diminish the area of immersion whereby with a sufficiently light boat and the necessary power the boat can be practically lifted 45 out of the water and even in some cases entirely off the water.

To enable my invention to be fully understood I will describe the same by reference to 50 the accompanying drawing which illustrates diagrammatically a boat constructed according to my invention.

Figure 1 being a sectional side view.

Fig. 2 a stern view.

Fig. 3 a plan, and

55

Fig. 4 a section on the line 4—4, Fig. 1.

Figs. 5 and 6 are respectively a side view and a plan illustrating the application of planes to the boat.

Figs. 7 and 8 are respectively a plan and 60 a stern view showing the connection of two boats, and

Fig. 9 is a section on the line 9—9, Fig. 7.

In these figures *a* indicates the inclined bottom and *b*, *b* the sides of the boat, the said 65 bottom having, as shown, the shape in plan view of an isosceles triangle, while the sides, which converge toward the stern, where a rudder *c* is fixed, are of approximately triangular shape in elevation.

70

For propelling the boat I propose to use submerged propellers such, for instance, as indicated at *d*, *d* and aerial propellers such for instance as indicated at *e*, *e* these propellers being operated by suitable motors, 75 which, in the drawing, are indicated diagrammatically at *f*.

The hull will usually be provided with a deck, say, as at *g*, the space beneath which will provide compartments for the motors, 80 for the accommodation of a crew, and for ballast tanks, such as *h*, *h*.

Although under normal circumstances and at a given speed a boat thus constructed would never wholly leave the water it 85 would be possible, either by increasing the speed to the requisite extent or by lightening the boat, for instance, by discharging ballast, for the boat to lift wholly off the water and pass over a break-water or other 90 obstruction, and to facilitate such an operation the boat may be provided with planes, say, as indicated at *i*. Figs. 5 and 6 such planes, when not required, being taken down and stored in the boat. The boat may also 95 be provided with masts and rigging.

It is to be understood that by the term inclined plane I do not limit myself to a plane which is rectilinear either longitudinally or transversely as the said plane may 100 have either a concave or convex curvature in either or both of these directions.

If desired two or more boats constructed as hereinbefore described may be connected together, as indicated, for example, in Figs. 105 7 to 9 wherein *k*, *k* indicate the two boats united at the bow as at *l* and connected together amidship and astern by ties or braces

m, n. Also the floats of hydro-planes can be constructed in the manner hereinbefore described.

Claims:

- 5 1. A boat including a hull having a triangular shaped bottom, the bow end of which is formed by the base of the triangle and the stern end of which is formed by the apex of said triangle, the bottom being gradually inclined downwardly from bow to stern, and said hull being balanced to cause substantially the front half of the hull to project above the surface of the water on which the boat floats.
- 10 2. A boat of the kind defined by claim 1 having an aerial propeller arranged at its bow for causing the boat to travel.
- 15 3. A boat of the kind defined by claim 1 having a water propeller at its stern normally occupying the water, and an aerial propeller at its bow.
- 20 4. A hydroplane comprising a hull hav-

ing a bottom which in plan is in the shape of an isosceles triangle, the bow end of the bottom being formed by the base of the triangle and the stern end being formed by the apex of said triangle, triangular shaped sides coöperating with the bottom to form the hull, and the bases of the triangular sides meeting at the stern of the boat, said bottom being gradually inclined downwardly from bow to stern and the hull being balanced to cause the front portion of the bottom to normally project above the surface of the water in which the hull rests, a propeller arranged at the stern and normally occupying the water, and an aerial propeller arranged at the bow.

25 5. A plurality of hulls of the kind defined in claim 1 having certain ends of the bows connected together and braces connecting the sterns and spacing the sterns apart.

30 35 CHARLES ALFRED JAMES.
